UNITED STATES PATENT OFFICE.

CLARENCE D. DOUGHTY, OF CONNERVILLE, OKLAHOMA.

WRENCH.

1,355,455.

Specification of Letters Patent.

Patented Oct. 12, 1920.

Application filed October 9, 1919. Serial No. 329,530.

To all whom it may concern:

Be it known that I, CLARENCE D. DOUGHTY, a citizen of the United States, residing at Connerville, in the county of 5 Johnston, State of Oklahoma, have invented certain new and useful Improvements in Wrenches; and I do hereby declare the following to be a full, clear, and exact description of the invention, such as will enable 10 others skilled in the art to which it appertains to make and use the same.

This invention relates to new and useful improvements in wrenches and particularly to ratchet wrenches.

15 One object of the present invention is to provide a novel and improved wrench for use on automobiles whereby access can be gained to nuts and bolts which are otherwise inaccessible with the ordinary 20 wrenches.

Another object is to provide a novel and improved wrench which includes means for turning a nut or bolt in either direction, with novel means for reversing the 25 table movements of the wrench.

Other objects and advantages will be apparent from the following description when taken in connection with the accompanying drawing.

30 In the drawing:

Figure 1 is a side elevation of a wrench made in accordance with my invention.

Fig. 2 is a vertical sectional view taken on the line 2—2 of Fig. 1, just inwardly of the 35 left hand side of the casing, as seen in Fig. 1, for the purpose of showing one of the pawl and ratchet means.

Fig. 3 is a vertical sectional view taken on the line 3—3 of Fig. 1, to the right of the 40 upper part of the shank of the wrench, as seen in Fig. 1.

Fig. 4 is a horizontal sectional view taken on the line 4—4 of Fig. 1, looking upwardly, to show the relative positions of the pawls 45 and ratchets, and the reversing means therefor.

Referring particularly to the accompanying drawing, 10 represents the shank of the wrench, which is formed with an apertured head at one end, as shown at 11. Disposed through the head, and rotatable therein, is a shaft 12, and secured on this shaft for rotation therewith, are the two ratchet wheels 13 and 14, said wheels being disposed 50 on opposite sides of the head, as shown. Outwardly of the respective heads are dis-

posed the plates 15 and 16, the former being formed with an opening at one end for the reception of the laterally turned end of the other plate, shown at 17, which passes 60 through an opening 18 in the intermediate portion of the shank. The said other plate has also an apertured head, and both of these heads of the plates receive the end portions of the shaft 12 rotatably therethrough. 65 On one end of the shaft there is formed a socket member 19 for the reception of the shank of a socket wrench head 20, said socket member 19 being provided with a screw 21 for retaining the wrench head in 70 position therein. Disposed transversely through the shank, between the shaft 12 and the laterally turned portion 17, is a pin 22, and mounted for pivotal movement on the ends of this pin are the pawls 23 and 24, the 75 former engaging with the teeth of the wheel 13, while the latter engages with the teeth of the wheel 14. These pawls, however, are disposed for engagement with the wheels from opposite sides, and the teeth 80 of the wheels extend in opposite directions, so that the shaft 12 may be rotated in opposite directions for the purpose of screwing on or off a nut. Disposed through the shank, between the pin 22 and the portion 85 17, is a pivot pin 25, and movably mounted on the ends of this pin, and on opposite sides of the shank, are the pawl releasing members 26 and 27. These members have their outer ends curved in opposite directions for engagement with the respective pawls 23 and 24, said members being rotatable with the pin so that when one is moved into engagement with the appropriate pawl to release the same from its ratchet wheel, 95 the other member will be moved away from its appropriate pawl.

By this construction the wrench may be operated to turn on or off a nut with equal facility, the pawl not needed being readily 100 and quickly released and the one needed thrown into operative position with respect to its ratchet wheel.

In the operation of the wrench it is only necessary to engage the wrench head with 105 the nut and then move the shank back and forth, with the result that the said head will be turned by the shaft, due to the action of the pawl in engagement with the proper ratchet wheel, said pawl moving idly back 110 over the ratchet wheel when the direction of the shank is changed.

Formed in the shank, adjacent the laterally turned portion 17, is an arcuate slot 28 in which is disposed a bolt 29, and held to the ends of this bolt by the nuts 30 are the 5 adjacent ends of the releasing members 26 and 27. This insures simultaneous movement of the two members.

What is claimed is:

A wrench comprising a shank having a 10 pair of longitudinal plates secured in spaced relation to one end of the shank and on opposite sides thereof, a transverse rotatable shaft disposed through the plates and shank and having a socket on one end, a 15 ratchet wheel secured on the shaft between one of the plates and the shank, a second ratchet wheel secured on the shaft between the other plate and the shank, pawls pivotally mounted on the shank and engaging re-

spectively with the ratchet wheels from opposite directions, a transverse pivot extending through the shank, the shank having a transverse arcuate slot between the plates, a pair of releasing levers mounted on the 20 said pivot on opposite sides of the shank and having pawl engaging ends extending in opposite directions, and a connecting means movable in the slot and connected to the levers, whereby upon movement of one of the levers said lever will engage and release the adjacent pawl and the other lever be moved away from the other pawl.

In testimony whereof, I affix my signature, in the presence of two witnesses.

CLARENCE D. DOUGHTY.

Witnesses:

R. H. VAUGHTER,
M. L. SHERRELL.
